UNITED STATES PATENT OFFICE.

HUBERT M. GRAF, OF KANSAS CITY, MISSOURI.

STEPLADDER.

1,397,280.

Specification of Letters Patent. Patented Nov. 15, 1921.

Application filed September 10, 1920. Serial No. 409,402.

To all whom it may concern:

Be it known that I, HUBERT M. GRAF, a citizen of the United States, and resident of Kansas City, county of Jackson, State 5 of Missouri, have invented a certain new and useful Improvement in Stepladders, of which the following is a complete specification.

This invention relates to step ladders, and 10 more especially to stepladders of that class employed by paper hangers and the like, and my object is to produce a stepladder provided with a vertically adjustable support or hanger for the support of one end of a 15 board to be used as a scaffold or platform by one or more workmen, the other end of the board being supported in any suitable manner either upon a stationary support or upon a duplicate of the stepladder.

20 Another object of the invention is to provide a folding stepladder provided with a vertically adjustable support for one end of the plank or board, which automatically assumes operative position when the stepladder 25 is open and inoperative position when the stepladder is closed.

With the general object in view mentioned and others of a secondary character as hereinafter will appear, the invention consists in 30 certain novel and useful features of construction and combinations of parts as hereinafter described and claimed, and in order that it may be fully understood reference is to be had to the accompanying drawing, 35 in which:—

Figure 1 is a perspective view of a step-ladder embodying the invention.

Fig. 2 is a fragmentary vertical section of the ladder taken in the plane indicated by 40 the line II—II on Fig. 3.

Fig. 3 is a horizontal section on an enlarged scale, taken on the line III—III of Fig. 2.

Fig. 4 is a horizontal section on the same 45 scale as Fig. 3, of the lower part of the plank supporting mechanism.

In the said drawing, 1 indicates the top of the stepladder, 2 the front legs thereof, and 3 the rear or pivoted legs adapted to 50 swing to folded position against the front legs when the step ladder is not in use, as customary. The step ladder is preferably made wider than the ordinary stepladder and is provided with a partition between 55 and parallel with the legs 2 and extending from the top to within a step's height of the

lower ends of the legs 2, the lower end of said partition 4 being secured to a cross step 5 connecting the legs 2 and constituting at one side of the partition, the bottom step 60 of the ladder, 6 indicating the intermediate steps between step 5 and the top, the intermediate steps extending from one of the legs 2 to partition 4. The legs 3 are also connected at a suitable point by a cross brace 65 7, and the opening of the stepladder is limited by a chain or cable 8, as customary in stepladders. The space between the other front leg of the ladder and the partition 4 is left unobstructed by steps for the accommodation of means for supporting one end of a plank to serve as a scaffold or platform between a pair of these step ladders or one of these stepladders and any other suitable support. 75

Referring now to the board or plank supporting mechanism, 9 indicates a pair of sleeves secured respectively to the partition 4 and the leg 2 having no connection with the steps 6, and pivotally suspended 80 from said sleeves and between the same, is a pair of parallel bars 10, connected rigidly together at their lower ends by a cross piece 11, and said bars 10 are provided with a vertical series of openings 12, and with metal 85 strips 13 provided with openings 14 registering respectively with the openings 12, the openings 14 being produced by stamping tongues from the metal strips and bending said tongues downwardly and outwardly so 90 that the openings shall be in effect ratchet-tooth shaped openings, the inclined sides of the openings being uppermost, as shown clearly by Fig. 2.

A slide-frame 15 fits snugly between the 95 strips 13 and is provided at its side edges with grooves slidably receiving or engaging the projecting edges of the strips 13, as shown most clearly by Fig. 3. The frame is provided with a horizontal partition 17 100 dividing it into a lower chamber 18 and an upper chamber or passage 19, said partition and the top of the frame forming a journal for a latch-operating shaft 20, provided with a handle 21 at its upper end by which it can 105 be manipulated, the lower end of said shaft terminating in a threaded portion engaged by a retaining nut 22 at the under side of the partition 17.

The flattened or central portion 20 of the 110 latch-operating shaft, is engaged at opposite sides by the hook-ends 23 of a pair of slidably

latches 24, the outer ends of said latches being tapered at their upper sides so that when engaged with a pair of the openings 14, an upward pull on the handle will draw the 5 slide upward, the latches sliding inward to permit of this action, it being likewise understood that the latches will prevent downward movement of the slide until the latches have been withdrawn from engagement with 10 said notches, and that the slide cannot be moved downward a greater distance than that between adjacent notches without first withdrawing the latches by grasping the said handle and turning the shaft so that its 15 flattened end shall apply inward pressure upon the ends of said latch bars respectively. The latch bars are guided for endwise movement by engagement with openings 25 in the sides of the frame, and by engagement with 20 vertical pins 26 secured to the frame and extending across the chamber or passage 19, the parts being so proportioned that the ends of the latch bars can never be wholly withdrawn through the sides of the frame. To 25 yieldingly advance the latch bars, they are provided with shoulders 27 and with expansive coil springs 28 which bear at their opposite ends against said shoulders and the pins 26. It will be understood that the springs 30 will yield to permit the latch bars to be withdrawn by turning movement of the shaft as above explained, or under the force exerted by the inclined faces of notches 14 on the beveled ends of the latch bars when the 35 slide is pulled directly upward.

To maintain the slide-carrying bars in vertical position, especially when the same are used to support the end of a plank fitted through the opening 18 and resting on the 40 lower portion of the slide, collapsible braces are employed. Adjacent their lower ends, the bars 10 are provided with channels 29 in their outer faces, and these channels are bridged by plates 30 secured to said bars 45 and provided with slots 31 narrower than and communicating with the channels 29. Headed bolts 32 extend slidably through the slots 31, and they are provided with heads or enlargements 33 for travel in the 50 channels 29.

It will be noted that the partition 4, and a corresponding partition 4^A extending from the cross piece 7 of the rear legs to the top, stand in a vertical plane and hence diverge 55 downward with respect to the adjacent legs 2 and 3 which are wider apart at the bottom than at the top and hence diverge downwardly, as shown most clearly by reference to Fig. 2, and that consequently, there is a 60 wider space between the plane of the right hand legs 2 and 3 of the stepladder and the adjacent bar 10, than between the other bar 10 and the said bars 4 and 4^A, and within said spaces are adapted to operate the folding 65 braces hereinbefore mentioned. Two of said

braces 34 and 35 are pivoted on one of the slideable pivots 32 and at their opposite ends respectively to the bars 4 and 4^A, and said braces are preferably so arranged that when the ladder is fully opened, the slideable bolts 70 to which they are pivoted assume a position slightly below the plane of the opposite ends of said braces, and thus acts to prevent collapse of the ladder until the joint is broken by sliding said bolt 32 upward. At the opposite side, a similar pair of braces 36 and 37 are pivotally connected to each other and to the other bolt 32 and to the adjacent legs 2 and 3 respectively, and these braces are 75 preferably of somewhat greater length than the first named braces so that the bolts 32 to which they are connected shall stand in a higher plane than the companion bolt 32, as shown most clearly by Fig. 2. The braces 36 and 37 also converge inwardly slightly by 80 reason of the greater space between the planes of the legs 2 and 3 to which they are attached and the adjacent bars 10, this inward slope of said braces serving to stiffen 85 the connection and act to guard against swinging movement to the right of the bars 10. A pair of cross braces 4^B are respectively secured diagonally of the rectangle formed by members 1, 4^A, 7 and 3 (see Fig. 1).

From the above description, it is apparent 95 that when the ladder is open, the parts assume the position shown in Fig. 1, and that a slight pressure on one of the braces 34 or 35 will depress the pivot bolts thereof below the planes of their outer ends and thus lock 100 the ladder against collapse, and while said parts are in this position, the slideable frame 15 can be disposed at the desired height and so secured by the engagement of the latch bars with a pair of the openings 14, and it 105 will be noticed that by reason of the unobstructed opening between partition bar 4 and leg 2 and bar 4^A and leg 3, a plank may be slid from either side through the opening 18 of the frame, or the adjacent end of two 110 planks may be fitted in said opening in overlapped relation, so that the latter may be utilized as a central support for a pair of planks. To close the ladder after the removal of the plank or planks, the joint between braces 34 and 35 will be broken upward as hereinbefore explained and then the ladder may be collapsed by swinging the legs 3 toward the legs 2. In this action, the pivot bolts 32 of both sets of braces will 115 slide upward in slots 29 and 31, and the ladder as a whole occupies no more room than an ordinary stepladder when folded.

As the various parts have been described in detail and their operation set forth, no 120 further recapitulation of the operation is deemed necessary, it being understood, however, that while I have illustrated and described the preferred embodiment of the invention, it is obvious that changes may be 125 130

resorted to without departing from the principle of construction involved or from the spirit and scope of the appended claims.

I claim:

5. 1. A stepladder, having an opening at one side of its steps, a pair of bars pivotally suspended within said opening, foldable braces between the said bars and the frame of the stepladder, and a vertically adjustable slide 10 on said bars.
2. A stepladder, having an opening at one side of its steps, a pair of bars pivotally suspended within said opening, foldable braces between the said bars and the frame of the 15 stepladder, said braces having a fixed pivotal connection with the frame and a slidable pivotal connection with said bars, and a vertically adjustable slide on said bars.
3. A stepladder, having an opening at one 20 side of its steps, a pair of bars pivotally suspended within said opening, foldable braces between the said bars and the frame of the stepladder, one set of the braces being shorter than the other set so that the pivotal 25 point of connection between the short set and the suspended bars can pass below the plane of their connection with the frame and lock the suspended bars against swinging movement when the ladder is open, and a vertically 30 adjustable slide on said bars.
4. A stepladder, having an opening at one side of its steps, a pair of bars pivotally suspended within said opening, foldable braces between the said bars and the frame of the 35 stepladder, one set of said braces being longer than the other set and converging inward from the said frame to their point of connection with the said suspended bars, and a vertically adjustable slide on said bars. 40
5. A stepladder, having an opening at one side of its steps, a pair of bars pivotally suspended within said opening, foldable braces between the said bars and the frame of the stepladder, a vertically adjustable slide on 45 said bars, and latch mechanism carried by said slide and adapted for engagement with said bars at predetermined points along their length.
6. A stepladder, having an opening at one 50 side of its steps, a pair of bars pivotally suspended within said opening, foldable braces between the said bars and the frame of the stepladder, a vertically adjustable slide on said bars, and latch mechanism carried by
- said slide and adapted for engagement with 55 said bars at predetermined points along their length, and means carried by said slide for disengaging the latch mechanism from said bars to permit adjustment of said slide.
7. A stepladder, having an opening at one 60 side of its steps, a pair of bars pivotally suspended within said opening, foldable braces between the said bars and the frame of the stepladder, a vertically adjustable slide on said bars, and latch mechanism carried by 65 said slide and adapted for engagement with said bars at predetermined points along their length, and means carried by said slide for disengaging the latch mechanism from said bars to permit adjustment of said slide, and 70 a rotatable handle for applying inward pressure on the latch mechanism to withdraw the same from engagement with said bars.
8. A stepladder, having an opening at one 75 side of its steps, a pair of bars pivotally suspended within said opening, and provided with a series of openings along their length, metal strips secured to the inner faces of said bars and of greater width than the same and provided with openings registering with 80 the openings of said bars and with downwardly and outwardly sloping tongues fitting in the said openings of said bars, a slide fitting between the said bars and provided at its side margins with grooves receiving the side edges of said metal strips, a pair of spring actuated beveled latches carried by said slide and projecting through the sides thereof and adapted for engagement with openings in said strips and bars, 85 and means carried by the slide for effecting withdrawal movement of said latch bars. 90
9. A stepladder, having an opening at one side of its steps, a pair of bars pivotally suspended within said opening, foldable braces 95 between said bars and the frame of the stepladder, a vertically adjustable slide fitting between and slidable on said bars and provided with an opening to receive the end of an object such as a plank, to be supported, 100 spring actuated latches carried by said slide for engagement with said bars to secure the slide at the desired height, and means carried by the slide for effecting withdrawal movement of said latch bars. 105

In testimony whereof, I hereto affix my signature.

HUBERT M. GRAF.
